UNITED STATES PATENT OFFICE

DAVID A. MEEKER, OF TROY, OHIO, ASSIGNOR TO THE KITCHEN AID MANUFACTURING COMPANY, OF TROY, OHIO, A CORPORATION OF OHIO

DESIGN FOR A FOOD MIXING APPARATUS

Continuation of application Serial No. D—35,046, filed March 27, 1930. This application filed January 12, 1932. Serial No. 42,453. Term of patent 14 years.

To all whom it may concern:

Be it known that I, DAVID A. MEEKER, a citizen of the United States of America, residing at Troy, in the county of Miami, State of Ohio, have invented a new, original, and ornamental Design for a Food Mixing Apparatus, of which the following is the specification, reference being had to the accompanying drawings, forming a part thereof.

The design is illustrated in the accompanying drawings which shows in

Fig. 1 a perspective view of food mixing apparatus showing my new design; and in

Fig. 2 a perspective view of the apparatus embodying the design, when viewed from the opposite side, and with a bowl shown in dotted lines.

As shown, the apparatus, embodying and

constructed to incorporate the design, comprises a base, a horizontally arranged casing portion, an interposed pedestal portion and a bowl.

This application is a continuation of an earlier filed design application,—David A. Meeker Serial No. D—35046, filed March 27, 1930, the disclosure of the present application differing from the said previously filed application in the manner of illustrating the embodiment of the design in the drawings. This cross reference is made for record purposes.

I claim:

The ornamental design for a food mixing apparatus as shown and described.

DAVID A. MEEKER.
